UNITED STATES PATENT OFFICE.

JAMES C. KITAMURA, OF LOS ANGELES, CALIFORNIA.

BUTLER'S GLOVE.

1,254,913.

Specification of Letters Patent. Patented Jan. 29, 1918.

Application filed June 17, 1916. Serial No. 104,637.

To all whom it may concern:

Be it known that I, JAMES C. KITAMURA, a subject of the Emperor of Japan, residing at Los Angeles, in the county of Los Angeles and State of California, have invented a new and useful Butler's Glove, of which the following is a specification.

An object of this invention is to provide a superior convenience for the use of butlers and other persons in the operation of dusting furniture, cleaning silver, polishing shoes, polishing furniture and any and all kinds of service where a dust cloth or polishing cloth may be used.

15 An object of this invention is to provide a glove that is convenient for such work as polishing silver, dusting furniture, polishing shoes with great ease and facility and without soiling the hands, and which is also adapted for convenient use after the manner 20 of an ordinary glove.

25 Other objects, advantages and features of novelty may appear from the accompanying drawings, the subjoined detail description and the appended claims.

The accompanying drawings illustrate the invention.

Figure 1 is a perspective view of a butler's glove constructed in accordance with this 30 invention, looking at the palm or inside of the glove.

Fig. 2 is a reduced view of the back or outside of said glove.

Fig. 3 is a fragmental cross section on line α^3 , Fig. 1, on an enlarged scale.

Fig. 4 is an enlarged cross-sectional view of another form of the butler's glove.

The body of the glove may be cheesecloth, canton flannel or any other desired flexible 40 sheet material of sufficient strength, and comprises the usual palm 1, thumb 2 and fingers 3 on the inner side and the back 4, thumb 2', fingers 3' on the back side. The front and back sides are connected together 45 in the usual manner of the art of glove-making by seams 5 located along the margins of the glove, there being in all ten marginal seams which only differ in length and location, and are therefore not indicated by separate characters.

50 Along the marginal seams and projecting inwardly, that is to say, toward the palm side of the glove, are a series of flaps 6, arranged in parallel sets; there being a

set of flaps at each edge or margin of the 55 glove body and at each side of the glove fingers including the thumb, there being ten sets in all and a plurality of flaps in each set. Said flaps at each edge of the fingers extend along the edges of the fingers continuously almost from end to end thereof and extend edgewise beyond one side of the fingers and are adapted to overlap and cover the intermediate faces of the same.

In some instances, as shown in Figs. 1 65 and 3, the flaps are made of plaits of flexible material, said material being doubled upon itself and sewn to the margins of the glove at the seams thereof. In other instances, as indicated in Fig. 4, the flaps 70 may be made of separate strips, the free edges 7 of which are single ply. The flaps may be of any desired width, and I have found that an inch or an inch and a half in width is very acceptable for common use. 75

The two sets of flaps for each finger are fastened at their closed edges to opposite sides of the fingers respectively and are of a width greater than the diameter of the finger, and they project laterally beyond the 80 finger so that they may combine to form a cover for that side; but may be easily separated to expose the wall of the finger so that the same may be used as the ordinary finger of a glove when the wearer wishes to 85 grasp an object therewith.

The flaps preferably terminate a little short of the finger ends, so that the tips 8 of the glove fingers may be formed of a single thickness of material free from the 90 flaps, so that the flaps may be easily separated to allow objects to be conveniently handled with the gloved hand.

In practical use the attendant will draw the gloves onto his hands in the usual manner of putting on gloves, and may then use the face, formed of the flaps to rub the furniture, silver, shoes or other objects that are to be dusted, polished or cleaned, and by thrusting the flaps aside, may use the fingers 100 to grasp objects as with the fingers of a common glove.

The gloves may be removed instantly, thus leaving the attendant free from the cleaning appliance.

I claim:

1. A glove comprising a body having fingers and flaps connected to the adjacent sides

of the fingers and extending edgewise beyond the front faces of the fingers and adapted to overlap to cover said faces, and to be separated to expose said faces.

5 2. A glove comprising a body having fingers and flaps connected to the adjacent sides of the fingers and extending edgewise beyond the front faces of the fingers and

adapted to overlap to cover said faces, and leaving the finger tips bare of flaps.

In testimony whereof, I have hereunto set my hand at Los Angeles, California, this 10th day of June, 1916.

JAMES C. KITAMURA.
